UNITED STATES PATENT OFFICE

MAX J. KELLING, OF WILMETTE, ILLINOIS

CONTAINER

Application filed August 9, 1929. Serial No. 384,684.

This invention relates to containers for confections, nut products and other edibles which should be carefully protected against contamination and changes in moisture content, but which should be so packaged that they may be attractively displayed. It is common practice to employ a transparent sheet material known as glassine in the packaging of edibles, but this material is open to the objections that it possesses little strength and is not moisture-proof.

There is available a tough, moisture-proof, transparent material known as cellophane, manufactured by the Du Pont Company, but it has not heretofore been practicable to employ this material in the production of a moisture-proof package for the reason that its moisture-proof property militates against the use of adhesive material in sealing the package.

The present invention makes possible the use of cellophane for the purpose stated.

The nature of the invention will be understood from the following description and from an examination of the accompanying drawing, in which:

Figure 1 is a sectional view of a container embodying the features of my invention.

Fig. 2 is a top plan view with the cover omitted.

Fig. 3 is an edge view with the cover omitted.

The drawings illustrate a container comprising a sheet-metal body portion A, a covering B of cellophane which closes the upper side of the portion A, and a sheet metal cover C which fits upon the body portion A and protects the cellophane covering B. While the container is herein shown as circular in outline, it will be understood that it may partake of various forms. The particular container shown in the drawings is especially adapted for nut products.

The body portion A comprises a bottom 1 and a circular side wall 2, said side wall being embossed to form an annular bead 3 that encircles the side wall 2 a slight distance above the seam or joint 4 between the bottom 1 and the side wall 2. The bead 3 and seam 4 project outwardly with respect

to the side wall and thus form between them an annular space which may be described as a shallow groove 5.

The cellophane covering B has a peripheral portion B' which surrounds the side wall 2 and which is held in place by means such, for example, as a narrow band 6 of paper which encircles the lower portion of the peripheral margin B'. The band 6 lies within the shallow groove 5 and is therefore held against displacement by means of the bead 3 and seam 4. The ends of the strip of paper 6 are overlapped and pasted together at 6'.

In practice, the body portion A is filled with the desired contents, after which a circular sheet of cellophane is laid upon the body portion A, the diameter of said sheet being such that its periphery projects beyond the periphery of the body portion A to an extent equal approximately to the height of the side wall 2. The cover C is then slipped upon the body portion A, in which operation the cellophane is drawn taut over the contents of the box and the peripheral portion of the sheet is bent down around the side wall 2. In thus assuming the form of an annular flange or margin, the peripheral portion of the sheet of cellophane becomes overlapped at irregular intervals as indicated at B² in Figs. 2 and 3. The cover C fits snugly over the side wall 2 and the interposed layer of cellophane. That part of the peripheral portion of the sheet of cellophane which extends below the cover C is then confined in place by means of a strip of paper 6.

It will be seen that the contents of the package may be attractively displayed beneath the transparent covering B, said cover preventing contamination and changes in moisture content. The paper strip 6 which tightly encircles the peripheral portion of the cellophane provides a substantially hermetic seal. The use of this band between two annular confining formations, such as 3 and 4, has solved the problem of securing a wrapping which is moisture-proof and thus not adapted to receive an application of adhesive material.

I claim as my invention:

A container comprising a body portion, a sheet of cellophane extending over the open side of said body portion and having a perimeter projecting beyond said body portion, a cover fitting over the upper portion of said body portion and confining the perimetral portion of said sheet of cellophane between itself and the body portion, there being an annular groove in the body portion below said cover, and a band lying in said groove and confining the peripheral portion of said sheet of cellophane.

In testimony whereof, I have hereunto affixed my signature.

MAX J. KELLING.
